UNITED STATES PATENT OFFICE.

JAMES M. DUDLEY, OF BESSEMER, ALABAMA.

RULING ATTACHMENT FOR TYPE-WRITERS.

1,299,436.

Specification of Letters Patent.

Patented Apr. 8, 1919.

Application filed September 14, 1917. Serial No. 191,424.

To all whom it may concern:

Be it known that I, JAMES M. DUDLEY, a citizen of the United States of America, residing at Bessemer, in the county of Jefferson and State of Alabama, have invented 5 certain new and useful Improvements in Ruling Attachments for Type-Writers, of which the following is a specification.

My invention relates to a ruling attachment for typewriters.

The object of my invention is to provide an attachment capable of ruling lines of uniform weight and of the same appearance as the typewriting itself, and is largely intended for the purposes and work set forth 15 in Letters Patent No. 1,247,514, issued to me on the 20th day of November, 1917; but provides important improvements in the specific construction of the ruling attachment and the manner of mounting it on different makes of typewriters, which largely facilitate the operation as well as reduce the costs of manufacture. To this end I use a 20 ruling roll and a ribbon to co-act therewith, which is preferably a ribbon similar to that 25 in use on the typewriter to which the device is attached.

One object of my invention is to provide a yielding spring pressure on the ruling roll 30 when held to its work, which materially aids in securing a uniformity of line and provides an automatic means of reducing the tension on the ribbon while it is in use against the paper.

A further object of my invention is to provide a simple means of shifting the ribbon 35 to secure a uniform wear and to almost completely use the ribbon surface. To be satisfactorily operable in the hands of the ordinary stenographer this ribbon shift must involve no careful adjustment of guides; furthermore, the control means to accomplish 40 this shift must be set away from the ribbon itself, so as to avoid soiling the fingers by 45 contact with the ribbon or rolls. To this end I provide a thumb screw outside of the spring frame roller container and thus accomplish both requirements with a simple means.

Furthermore, my invention, as well as being attachable to a type of machine provided with a holding means for pencils, pens, or like scribes, is by means of a novel supporting and clamping attachment made adaptable to any typewriter.

As illustrative of the preferred embodi-

ment of my invention, reference is made to the accompanying drawings, wherein,

Figure 1 shows my invention attached to a special make of typewriter which is provided with a holding means for scribes.

Fig. 2 is a front elevation of my ruling attachment.

Fig. 3 is a side elevation of Fig. 2.

Fig. 4 is an enlarged perspective detail of 65 one of the roll bearings showing the ribbon retaining guides.

Fig. 5 is a plan view of a typewriter wherein no provision is made for a ruling device, and shows my ruling attachment 70 held in operating position by means of a novel supporting and clamping means.

Fig. 6 is a front elevation of Fig. 5 and shows the relative position of the typeline, 75 the path of the nearest type bar, and how the ruling attachment is positioned to operate on this type line yet clear the path of the type bar.

Fig. 7 is a perspective view of the supporting clamp.

Similar reference numerals refer to similar parts throughout the drawings.

Where my invention is to be attached to a typewriter 1 provided with a holder 2 for a scribe, I provide a shank 3 adapted to fit 85 closely and be clamped by any suitable means in the holder. This shank at its lower end is turned down to form a shoulder 4 onto which is set the upper horizontal portion 5 of a spring yoke 6. The joint is preferably formed by passing the shoulder 4 through a hole in the portion 5 and then riveting in place. Depending from the horizontal portion 5 and formed integral with it, are two similar parallel legs 7, which 90 reduce in width at 8 and turn symmetrically outward to form a semi-circular or bowed spring portion 9 and finally terminate in short bearing ends 10, which are in line with the portions 7 and except for the semi-circular offset form a continuation of the legs 7. The bearing ends 10 have holes 11 adapted to receive and permit a free rotation of the trunnions 12 of the ruling roll. The 95 ruling roll is preferably formed integral 100 with its end trunnions 12, and comprises a cylindrical body 13 with a sharp annular ruling edge 14. The ruling edge can be continuous or formed with points to rule a continuous or a dotted line. The cylinder 13 is 105 of length substantially equal to the spacing between the parallel bearing ends 10, when

110

the legs of the frame are not under tension, and the reduction in diameter of the cylinder 13 to form the trunnions 12 provides shoulders forming end bearings, which prevent lateral displacement of the ruling roll in the frame. On the outer side of one of the legs 7, near its upper end a hole is punched to receive a tapped boss 16 preferably riveted in place. Through this tapped boss 16 I pass a screw 17 having a threaded portion 18, terminating at one end in a knurled head 19 and having its other end turned down to form a cylindrical portion 20, thereby forming a shoulder 21 at the end of the threads. Mounted on this cylindrical portion 20 is a roller 22 having at each end flanges 23. After the roller 22 is in place the end of the cylindrical portion 20 is upset to form a head and the roller is prevented from end play by this head and the shoulder 21. Over the ruling roll and the roller 22 is passed the endless ribbon 24.

To mount the ribbon upon the rolls it is passed around the open end of the screw 17 and over the flange 23. The spring legs 7 are then spread until one of the trunnions 12 is removed from its bearing 11 and the ribbon passed over this open end, whereupon the released trunnion 12 is forced again to its bearing position and the ribbon is in place.

To shift the ribbon so as to utilize practically its entire surface it is only necessary to turn the screw 17, which moves the flanged roller 22 laterally in the yoke 6, thereby causing the two rollers to be out of line and the ribbon acting as a belt upon operation shifts itself to alignment and moves a fresh surface to the annular ruling edge. To prevent the ribbon from slipping from the ruling edge when it is being used in its extreme positions the bearing ends 10 are provided with guiding extensions 10^a which engage the outer edge of the ribbon, as it approaches and leaves the ruling roll, and prevent extreme lateral adjustment which would permit the ribbon to leave the ruling edge.

When my invention is to be applied to a typewriting machine not provided with the holder 2, I have designed a support and clamp means which would then, with my ruling device, constitute the attachment. For clearance of the various standard parts I prefer to mount my support and clamp means upon the upper horizontal frame plate 24^a. The clamp is preferably stamped from sheet metal and comprises a body portion 25, which at one end is downturned to form a clamping flange 26, and its other end extends inwardly over the type bars to form a bearing support 27 near the platen. To securely fasten this end 27 to the plate 24^a two downturned hook like fingers 28 are passed over the inner edge flange of the

plate 24^a and are hooked under the lower edge of this flange. With these fingers and the flange 26 the clamp and support means is prevented from lateral movement, but to secure it against vertical displacement a thumb screw 29, having a conical point 30 is provided in the flange 26 at a position which will cause the conical point 30 to engage the lower edge of the outer flange of the plate 24^a and by a wedging action clamp the plate 25 in position. The plate is also adapted, where such exists on the frame 24^a, to be held in place by a bearing on one side against the ribbon guide 41 and on its opposite side against the cross bar support 42. To strengthen the support 27 I bend down a side flange 43 extending with increasing width from the outer end of the support along one side edge to and abutting against the inner edge of the frame plate 24^a. To move the ruling device against the platen a lever 31, formed preferably of a rod or bar, is pivoted by a screw 32 to the inner overhanging end of the bearing support 27 of the plate 25. This lever has its inner end 33 bent horizontally substantially at right angles toward the platen 35 of the typewriter and enters a hole 34 in shank 3 of the ruling device where it is firmly secured. The lever 31 extends across the plate 25 and at its outer end is bent down to form a pull handle 36. In order to steady the lever and insure an absolutely rigid movement of the ruling device, I punch from the flange 26 a hold down flange 37, having its outer edge struck on an arch from the center of the fulcrum 32 of the lever. At 38 I bend the arm 31 around the curved edge of this hold down flange 37, so as to prevent vertical displacement of the lever. A stop 40 is formed on the end of arc 37 to retain the arm 31.

It will be noticed, Fig. 6, that the path of the nearest type bar, as well as the ribbon is not obstructed by the attachment.

In operation, the ruling device being in position on the support provided with the typewriter, when it is desired to rule a line on the paper, the device is pressed against the platen and the carriage released so as to permit a free movement of the platen under the roll of the device. After a number of lines have been made and the ribbon appears worn, the thumb screw is turned in either direction, just sufficiently to shift a new area of the ribbon under the ruling edge.

In operation, when the ruling device is used with the supporting and clamping means to form a complete attachment, and the attachment in clamped position, it is only necessary to draw the pull handle 36 toward the operator with one hand while the other operates the carriage release to move the platen carrying the paper beneath the ruling roll. All ribbon adjustments and operations

are performed the same as when the ruling device is used separately.

What I claim as new and desire to secure by Letters Patent, is:

- 5 1. A typewriter ruling attachment, comprising a roll having a ruling edge, a spring frame comprising flexible arms in which the roll is journaled, and a movable ribbon interposed between the roll and the surface
- 10 to be ruled.
2. A typewriter ruling attachment, comprising a roll having a ruling edge, a U-shaped frame in the open end of which said roll is journaled, a ribbon guide in the frame, and an endless ribbon working about the roll and guide, said frame opposite the ends of said roll being widened to form side guides for the ribbon.
3. A typewriter ruling attachment, comprising a U-shaped frame having flexible sides, a ruling roll having end trunnions detachably mounted to rotate in the free ends of said sides, and means to guide a ribbon between said roll and the surface to be ruled.
- 25 4. A typewriter ruling attachment, comprising a U-shaped frame having flexible outwardly bowed sides, a ruling roll having at one end a reduced end trunnion, means to journal the other end of said roll in one side of said frame, the other side of said frame being perforated to receive said trunnion and being flexible enough to be sprung over the same to free one end of said roll, and means to guide a ribbon between
- 30 35 said roll and the surface to be ruled.
5. A typewriter ruling attachment, comprising a yoke having spring sides bowed outwardly, a ruling roll journaled in the open end of said yoke, and means to interpose a movable ribbon between said roll and the surface to be ruled.
- 40 6. A typewriter ruling attachment, comprising a yoke frame, a ruling roll journaled in the open end of said frame, said frame comprising yieldable arms adapted to be sprung apart to release the roll, and a ribbon guide extending part way across the closed end of said frame.
- 45 7. A typewriter attachment, comprising a yoke frame, a ruling roll journaled in the open end of said frame, at least one side of the frame being movable to readily detach it from the roll, and a flanged ribbon guide mounted on one side only of said frame
- 50 55 near its closed end.
8. A typewriter ruling attachment, comprising a yoke frame, a ruling roll journaled in the open end of said frame, at least one side of the frame being detachable from said roll, a flanged ribbon guide roller rotatably mounted on one side only of the said frame near its closed end, and means to laterally adjust said roller.
9. A typewriter ruling attachment, comprising a frame, an element provided with a ruling edge mounted at one end of said frame, a ruling ribbon, a guide roller for said ribbon, and a laterally disposed screw adjusted bearing for said guide roller mounted near the other end of said frame.
10. A ruling attachment for typewriters, comprising a frame carrying a ruling roll, means to present a ribbon between the surface to be ruled and said roll, a tubular shank on the frame, and a movable typewriter attachment adapted for attachment to said shank.
11. A typewriter attachment, comprising a lever having a ruling roll journaled in its inner end, a handle at its outer end, a ribbon coacting with said roll, and a rigid bearing for said lever which is overhung from the typewriter frame toward the printing site on the typewriter platen.
12. A typewriter attachment, comprising a bracket having means to attach it to a typewriter, a lever fulcrumed on the bracket, a ruling roll journaled on the inner end of the lever, a ribbon with which the roll coacts, and an operating handle on the outer end of the lever, the bracket having a hold-down flange an edge of which is struck on an arc from the lever fulcrum, and a lip on the handle end of the lever disposed to travel under said curved edge of said flange.
13. A typewriter attachment, comprising a bracket having a down-turned hook adapted to catch under the inner edge of a typewriter top and having a down turned flange over lapping the outer edge of said top, means to rigidly secure said bracket on the said top, an inward extension on the bracket reinforced and carrying a vertical pivot pin, a lever journaled in said pin and adapted to swing horizontally, a ruling means on the inner end of said lever, and means to move said lever into and out of ruling position.

In testimony whereof I affix my signature.

JAMES M. DUDLEY.
